COUNTING DEVICE

Hans Bud, London, England

Application December 12, 1950, Serial No. 200,357

Claims priority, application Great Britain
December 21, 1949

9 Claims. (Cl. 235—117)

1

The present invention relates to a counting device of the kind comprising a plurality of digit wheels and a rotatable spindle coupled to one of the digit wheels for rotating it, a transfer mechanism being provided for transferring rotational movement of a digit wheel, while passing through a predetermined position, to another digit wheel. Usually, the spindle is coupled to the unit-digit wheel, and the transfer mechanism becomes operative when a digit wheel passes from the position corresponding to its digit "9" to the position corresponding to its digit "0" and/or vice versa.

In use, the rotatable spindle may be connected to a driving element, for example, a driving shaft, the number of rotations of which are to be counted.

Although, particularly in the case of die-cast digit wheels, the weight of such wheels may be kept low and the required torque small, it has been found that the transfer mechanism and/or the digit wheels are liable to undue wear during use, if the counting device is frequently started and stopped with excessive or uncontrolled acceleration or deceleration.

It is an object of the present invention to provide a counting device wherein this drawback is avoided or, at least, decreased.

To this end the invention provides a resilient coupling between the rotatable spindle and one of the digit wheels.

It is another object of the invention to provide a counting device of a neat, compact and inexpensive construction which is rendered possible by providing the resilient coupling between the rotatable spindle and the digit wheel, and not between the said spindle and a shaft driving the spindle.

It is a further object of the invention to provide a counting device having a resilient coupling between the rotatable spindle thereof and a digit wheel, wherein means are provided for coupling the said spindle to the said digit wheel non-resiliently or less resiliently when in use the resilient coupling becomes damaged or worn out, whereby to enable continued use of the counting device for, at least, a limited further period.

Other objects and advantages of the invention will become apparent to those skilled in the art from the following description of an embodiment of the invention when read in conjunction with the accompanying drawings, wherein:

Fig. 1 is a perspective view of a counting device of the invention;

Fig. 2 shows the device of Fig. 1 when viewed in the direction of the arrow II, some parts being broken away;

2

Fig. 3 is a plan view of a detail of the device of Fig. 1 viewed in the direction opposite that indicated by the arrow II;

Fig. 4 is an exploded view of the coupling mechanism of the device; and

Fig. 5 is a plan view of another detail of the device of Fig. 1 viewed in the direction of the arrow II.

Referring now to the drawings, the counting device generally denoted by numeral 1 comprises a casing 2 having a flange 3 with holes 4 therein for fixing the device, for example by means of screws (not shown), in any convenient position. The counting device 1 comprises a plurality of

15 digit wheels, five in the drawings, the digits marked thereon being visible through a window 5 in the casing 2, a rotatable spindle 6 being resiliently coupled to the digit wheel 7, this being the unit-digit wheel in the embodiment shown, a 20 transfer mechanism 8 (see Fig. 4) being provided for transferring rotational movement of a digit wheel, while passing through a predetermined position, to another digit wheel. Some of these components, such as the casing and the digit 25 wheels may be made by die-casting.

The resilient coupling between the rotatable spindle 6 and the unit-digit wheel 7 comprises a disc 12 on the rotatable spindle 6 and rotatable therewith. The disc 12 has a recess 13 open towards its circumference 14 and towards its side 15 shown in plan view in Fig. 3 and facing the unit-digit wheel 7 to be coupled to the rotatable spindle 6. The width of the recess 13 decreases in the radial direction of the disc 12 towards the circumference 14 thereof so that a resilient block 16 of rubber or synthetic rubber may be introduced into the recess 13 from the said side 15, the block 16 protruding beyond the circumference 14 of the disc 12 and being prevented from leaving the recess 13 in the radial direction of the disc by the decreasing width of the recess 13.

The unit-digit wheel 7 to be coupled to the rotatable spindle 6 has a circumferential shoulder 17 at its side facing the disc 12, the shoulder 17 having a recess 18 adapted to receive that portion of the resilient block 16 which protrudes beyond the circumference 14 of the disc 12. The disc 12 has such a size that, when the arrangement is assembled, the disc 12 is surrounded by the shoulder 17 of the unit-digit wheel 7 and the protruding portion of the resilient block 16 engages the recess 18 in the shoulder 17 and thereby effects the resilient coupling between the disc 12 (and, thus, the rotatable spindle 6) and the shoulder 17 (and, thus, the adjacent unit-digit wheel 7). A retaining washer 19 idling on the spindle 6 is

40 45 50 55

inserted between the disc 12 and the unit-digit wheel 7 so as to be surrounded by the shoulder 17, whereby to prevent the block 16 from becoming disengaged from the disc 12 and from interfering, or causing friction, with stationary members of the counting device. The height of the shoulder 17 is such that when the arrangement is assembled that side of the disc 12 which is remote from the unit-digit wheel 7 is substantially flush with the free edge of the shoulder 17. 10

In order to effect a non-resilient or less resilient coupling between the disc 12 and the unit-digit wheel 7 when the resilient block 16 becomes worn out, the circumference 14 of the disc 12 is flattened at both sides of and adjacent to the recess 13 in the disc 12, and the shoulder 17 of the unit-digit wheel 7 comprises two projections or beads 20, one at each side of the recess 18 in the shoulder, the projections or beads 20 being directed towards the circumference 14 of the disc 12. The said circumference 14 is flattened to such an extent that the said projections or beads 20 do not contact the circumference 14 of the disc 12 while, owing to the resilient coupling effected by the resilient block 16, the recess 13 in the disc 12 substantially registers with the recess 18 in the shoulder 17. When, however, the resilient block 16 becomes, in use, worn out, the disc 12 on being rotated in one direction slips relatively to the adjacent unit-digit wheel 7 until one of the two projections or beads 20 on the shoulder 17 of the unit-digit wheel 7 contacts the circumference 14 of the disc 12 and prevents further slipping of the disc 12 relatively to the unit-digit wheel 7 in the said direction, whereby a non-resilient coupling or, if the resilient block is not sufficiently worn out, a less resilient coupling is effected.

Thereby it is rendered possible to continue using the counting device for, at least, a limited further period until the worn-out block can conveniently be replaced by a fresh block, or until the increased wear resulting from the non-resilient or less resilient drive causes a final breakdown.

After the arrangement has been assembled the casing 2 may be closed at its open end (which is the rear end when viewed as shown in Fig. 1) by a lid 21, which may be fixed to the open end of the casing 2 in any convenient manner, and may, if desired, be sealed thereto.

Modifications of the embodiment described are possible. For example, instead of the flange 3 the casing may have other fixing means, such as a plurality of flanges or a gib. The resilient block may be replaced by any other suitable spring means, such as a leaf-spring or springs, or a coiled spring or springs. Again, instead of providing one resilient block 16, a plurality of such blocks may be arranged on the disc 12, for example at diametrically opposed regions. The block or blocks may be held on the disc by means other than those described and may engage the shoulder of the digit wheel in any other suitable manner. For example, the block may be riveted to the disc and abut against abutment means. The resilient block or blocks may be fixed to a digit wheel and may engage a recess or recesses in the disc 12. The rotatable spindle may be coupled to a digit wheel other than the unit-digit wheel.

It should be clearly understood that the attached drawings are given by way of example only. Many modifications of, omissions from, and additions to, the embodiment illustrated are

possible without departure from the spirit of this invention as defined in the appended claims.

I claim:

1. A counting device comprising a plurality of digit wheels, a rotatable spindle, a disc on said rotatable spindle and rotatable therewith, said disc having a recess, a block of resilient material held in said recess, a portion of said block of resilient material protruding radially from said recess beyond said disc, and a shoulder on one digit wheel, said shoulder having another recess engaging the protruding portion of the block of resilient material.

2. A counting device as claimed in claim 1, wherein the width of the recess in the disc decreases in the radial direction of the disc towards the circumference thereof so as to prevent the block of resilient material from leaving the said recess in the radial direction.

3. A counting device as claimed in claim 1, wherein the disc is surrounded by the shoulder on the digit wheel, and the height of the shoulder is such that the side of the disc remote from the digit wheel is substantially flush with the free edge of the shoulder.

4. A counting device as claimed in claim 1, and comprising a projection on the shoulder at a side of said other recess, the said projection being directed towards the circumference of the disc, the said circumference of the disc having a flattened portion adjacent the recess in said disc, the said projection having such a length that it normally is out of contact with said flattened portion of the circumference of the disc but is capable of contacting the non-flattened part of said circumference the arrangement being such that normally owing to the resilient coupling effected by the resilient block, the recess in the disc substantially registers with said other recess in the shoulder, whereas, when the said resilient block becomes in use worn out, the disc on being rotated in the appropriate direction slips relatively to said shoulder on the said one digit wheel until the said projection on said shoulder contacts the circumference of said disc and prevents further slipping, whereby a non-resilient coupling is effected.

5. A counting device comprising a plurality of digit wheels, a rotatable spindle, resilient means for coupling the said spindle to one of the digit wheels for rotating it, abutment means on said one digit wheel, a disc on said rotatable spindle and rotatable therewith, a block of resilient material forming a part of the resilient coupling means and being held by said disc, a portion of said block of resilient material protruding radially beyond said disc, and a shoulder forming another, complementary, part of the resilient coupling means and being provided on said one digit wheel for engagement with the protruding portion of said block of resilient material.

6. In a counting device, the combination of two rotatable members, at least one of the said rotatable members being a digit wheel, a disc on one of said rotatable members and rotatable therewith, a block of resilient material held by said disc, a portion of said block of resilient material protruding radially beyond said disc, and a shoulder provided on the other rotatable member and arranged for engagement with the protruding portion of said block of resilient material to provide a resilient coupling between the said two rotatable members.

7. A counting device as claimed in claim 6, and comprising abutment means on one of said two rotatable members, and further abutment means as-

sociated with the other rotatable member and rotatable therewith, the said abutment means and further abutment means being arranged for co-operation with each other when the said resilient coupling becomes damaged in use whereby thereafter to enable continued use of the counting device for at least a limited period by a non-resilient coupling between the said two rotatable members through the said abutment means and further abutment means.

8. A counting device as claimed in claim 6, wherein the other rotatable member is a rotatable spindle.

9. In a counting device, the combination of two rotatable members, at least one of the said rotatable members being a digit wheel, means for resiliently coupling the said two rotatable members, a non-resilient abutment means rigid with one of the said two rotatable members, and a further non-resilient abutment means rigid with the other rotatable member, the said abutment means and further abutment means being normally separated from each other by an air gap maintained by the action of the said resilient coupling

means when fully effective, the said abutment means and further abutment means being arranged for co-operatively abutting against each other when the said resilient coupling means becomes defective in use and consequent slipping between the said two rotatable members occurs, whereby thereafter to enable continued use of the counting device for at least a limited period.
